FIG. 4.

UNITED STATES PATENT OFFICE.

HENRY D. CONWAY, OF JACKSON, MICHIGAN.

HOPPER.

SPECIFICATION forming part of Letters Patent No. 741,112, dated October 13, 1903.

Application filed February 27, 1903. Serial No. 145,434. (No model.)

To all whom it may concern:

Be it known that I, HENRY D. CONWAY, a citizen of the United States, residing at Jackson, in the county of Jackson and State of Michigan, have invented certain new and useful Improvements in Hoppers, of which the following is a specification.

This invention provides a hopper designed chiefly to facilitate building operations in the construction of walls of plastic material, same being of such formation as to enable the body portion of the wall to be of coarse or poor material and the facing to be rich or of fine material to present a good, substantial, and durable finish.

A further purpose is the provision of a hopper readily adjustable to different thicknesses of walls and which will withstand the hard usage to which it will be subjected in operation. The hopper is partitioned to separate the different materials, the partitions projecting a distance below the hopper to keep the said materials apart except for proper bonding essential to form a homogeneous wall.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a view of the hopper as seen from the front end. Fig. 2 is a view from the rear end, the section-lines showing the form upon which same is mounted. Fig. 3 is a top plan view, the intermediate portion being broken away. Fig. 4 is a side elevation.

Corresponding and like parts are referred to in the following description and indicated in all the views of the drawings by the same reference characters.

The hopper may be of any length and width and is of rectangular formation in plan view, the ends preferably being parallel and vertical and the sides upwardly flared. The several parts are preferably constructed of metal,

same being reinforced wherever required to strengthen and stiffen the walls.

The sides 1 and 2 are provided at their ends with inner flanges 2^a, forming stops to prevent outward displacement of the ends. The flanges 2^a are an integral part of the sides and are formed by bending end portions thereof at a right angle. Angle-irons 3 are secured to the sides 1 adjacent to their flanged ends and are spaced from flanges 2^a a distance corresponding to the thickness of the ends of the hopper for reception thereof. The parts 2^a and 3 constitute guides or stops for embracing edge portions of the ends and securing the latter from either outward or inward displacement. The parts 2^a and 3 also constitute reinforcements, as will be readily comprehended.

The ends 4 and 5 of the hopper may be of any width corresponding to the thickness of wall to be constructed, and their edge portions are fitted between the stops or guides 2^a and 3. The bottom edge of the end 5 is preferably straight, whereas the corresponding edge of the end 4 is concave or hollow to admit of readily clearing the portion of wall constructed when shifting the hopper to a new position. The upper edges of the ends 4 and 5 are convex or upwardly curved, thereby admitting of keeping the material between the sides. The edges of the ends are upwardly sloped, corresponding to the upward flare of the sides of the hopper, thereby admitting of a gradual compacting of the material in its descent through the hopper to the form.

Longitudinal partitions 6 and 7 subdivide the hopper, so as to form spaces 8, 9, and 10 for reception of the different grades of material. The end portions of the partitions are bent at a right angle to form flanges 11, which receive the bolts or other fastenings 12, connecting the partitions to the end supports. One of the longitudinal partitions, as 7, terminates a distance from the end 4 of the hopper and is connected to a transverse partition 13, which forms with the end 4 a space 14 for receiving the material forming the facing of an opening or return at the corners of walls. The inner end of the transverse partition 13 is bent to form a flange 15, which is secured

by fastenings 12 to the longitudinal partition 6, the outer end being received between stops or guides 16, secured to and extended in from the side 2. Said stops or guides 16 are wings 5 or parts of angle-irons attached to the side 2 and spaced apart a distance to snugly receive the outer end of partition 13. The outer edge of partition 13 slopes to correspond with the inclination of the corresponding edges of 10 parts 4 and 5, and said partition, like the ends 4 and 5, will be provided in different widths to adapt the hopper for different thicknesses of walls.

Diagonal braces connect the sides 1 and 2 15 at their ends and involve a sectional construction to admit of lengthening and shortening the braces, according as the sides of the hopper are to be separated or brought together. The braces are indicated at 17 and are composed of companion bars pivotally connected 20 at their ends to the corners of the respective sides, said bars being longitudinally slotted, as shown at 18, and receiving a bolt or fastening 19 at the point of crossing, said fastening 25 passing through the slots of the four bars. The companion bars of the respective braces are alternately arranged and are spaced apart at their pivotal ends by means of washers 20, slipped upon the pivot-fastenings 21 and arranged 30 between said bars. This construction is shown most clearly in Figs. 3 and 4, which indicate the two bars of each brace spaced apart, with one bar of each set or pair of bars passed through the space formed between the 35 bars of the other set or pair, thereby resulting in the alternate arrangement herein described. By loosening the bolts or fastenings 19 the sides 1 and 2 may be separated or brought together and when properly positioned are made secure by retightening the 40 fastenings 19.

Angle-bars 22 are rigidly attached to the lower edge portions of the sides 1 and 2 and serve the double purpose of stiffening and 45 strengthening same, besides forming a support for wheels 23, which are adapted to travel upon the upper edge of the form 24. After the form has been set up the hopper is placed thereon about as indicated in Fig. 1 and is 50 shifted by being moved upon the wheels 23. The several partitions project below the walls of the hopper, so as to enter the space inclosed by the form to an extent to insure proper separation of the different kinds of 55 material. It is to be understood that the hopper is moved before the material sets. Hence the filling and the facing materials are enabled to come together to form a bond, whereby the wall is, in effect, homogeneous. The 60 poor material is supplied to the space 9 and the facing material to the spaces 8, 10, and 14. By reason of the extension of the partitions into the space of the form the different kinds of materials may be supplied to the 65 hopper at different times, the mixing being prevented by the pendent portions of the

partitions, as will be readily comprehended. The hopper is removed before the material sets; hence same can settle so as to unite and form, in effect, a single solid wall comprising 70 a central portion of coarse or poor material and an outer portion of fine rich material.

The sides of the hopper may extend parallel, if desired; but it is preferred to have them upwardly flared. By having the lower 75 edge of the rear wall 4 upwardly curved sufficient material is left after the hopper is moved forward so as to come level with the form after being tamped.

Having thus described the invention, what 80 is claimed as new is—

1. A hopper comprising side and end walls, the side walls being provided at their ends with spaced stops or guides to receive and embrace edge portions of the end walls, and 85 means for connecting the side walls, substantially as set forth.

2. A hopper for the purpose described comprising end and side walls, the side walls having their end portions bent inward to form 90 stops or guides, other stops secured to the side walls adjacent to their bent ends to form coöperating stops or guides for reception of the edge portions of the end walls, and means for connecting said side walls, substantially 95 as described.

3. A hopper comprising end and side walls, guides at the ends of the side walls for reception of the edge portions of the end walls, and braces connecting the side walls and having a diagonal arrangement and pivoted at 100 their ends to the corners of the side walls and firmly secured at the point of crossing, substantially as set forth.

4. A hopper comprising side and end walls, 105 diagonally - arranged braces connecting the side walls, each set of braces comprising slotted companion bars pivoted at their outer ends to the respective corner portions of said sides, the bars of corresponding braces having an alternate arrangement, and a fastening connecting the several bars of the braces at the point of crossing, substantially as set forth.

5. A hopper for the purpose set forth comprising separated spaces, one for reception of poor or coarse material and the other for reception of rich or fine material to form a facing to the body formed by the poor material, substantially as specified. 115

6. A hopper comprising side walls having spaced stops at their ends, end walls having their edge portions loosely fitted into the spaces formed by the respective stops, a partition forming a tie for and connecting the 125 end walls, and means for securing the side walls, substantially as set forth.

7. A hopper comprising side walls having spaced stops near their ends, end walls having their edge portions loosely fitted into the 130 spaces formed by the respective stops, a longitudinal partition firmly attached at its ends

to said end walls, a transverse partition secured to the longitudinal partition, spaced stops applied to a side wall of the hopper to receive the outer edge portion of the transverse partition, and means for connecting the side walls, substantially as described.

8. A hopper comprising side walls provided at their ends with spaced stops, end walls, a longitudinal partition connecting said end walls, a transverse partition secured to the longitudinal partition, a second longitudinal partition connecting the transverse partition with an end wall, spaced stops applied to a side wall for reception of the outer edge portion of the transverse partition, and means

for connecting the side walls, substantially as specified.

9. A hopper for the purpose stated, subdivided by a partition to form spaces to receive different kinds of material, said partition extending below the walls of the hopper to properly separate the different kinds or grades of material substantially as described.

In testimony whereof I affix my signature in presence of two witnesses.
